METHOD FOR MAKING IMITATION TILE

Samuel B. Collins, Bayonne, N. J.

Application June 3, 1933, Serial No. 674,133

3 Claims. (Cl. 41—24)

This invention relates to a wall covering in imitation of tile.

One object of the present invention is a reduction in the cost of such wall covering. To this end, the wall covering is made in sheets, in simulation of one or more tiles, which sheets are adapted to be applied to the surface of a wall by means of an adhesive. Preferably, such sheets are of a fibrous material, in whole or in part.

Another object of the invention is a wall covering in simulation of tile which is washable and unaffected by moisture in contact with its surface. To this end, the exposed surface of the wall covering is coated with a water resistant layer, such, for instance, as a layer of some derivative of cellulose acetate or a synthetic resinoid.

It is also an object of the invention to provide a wall covering in simulation of tile which shall have the characteristics of tile insofar as retention of shape is concerned. Accordingly, a sheet of fibrous material, which is pressed outwardly into the form of a tile, has in the pressed out portion reenforcement of either a fibrous, 25 solidified plastic or congealitious material.

The invention also has to do with a method of manufacturing a wall covering in simulation of tile which is practical from the standpoint of ease and cheapness of manufacture, convenience 30 in application and durability in use.

These and other objects of the invention and the means for their attainment will be more apparent from the following detailed description, taken in connection with the accompanying 35 drawings illustrating various embodiments by which the invention may be realized, and in which:

Figure 1 is a view, in perspective, showing a sheet of fibrous material such as heavy paper 40 composition or the like upon which the representation of one or more tiles is depicted;

Figure 2 is a view in transverse section showing a form of embossing dies by which the sheet of Figure 1 may be shaped to simulate tile;

Figure 3 is a perspective view showing the finished wall covering simulating four tiles;

Figure 4 is a view, partly in perspective and partly in section, on an enlarged scale, showing one method of reenforcing the outwardly pressed 50 portions;

Figure 5 is a view similar to Figure 4 but showing another method of reenforcement;

Figure 6 is a view, partly in elevation and partly in section, showing the application of one 55 form of the wall covering to a surface;

Figure 7 is a fragmentary view showing another modification of the invention in which the use of an additional reenforcing element is avoided; and

Figure 8 shows the completed article.

While the size of the various sheets of wall covering to be applied to the wall may vary, there is illustrated in Figure 1 a plane sheet 10 of, say, fibrous material upon one surface of which are printed representations of four tiles 10 suitably spaced as vitreous tile would be when in place on a wall. These representations of tile take the form of square areas 12 separated by fairly wide lines or areas 14 of, at least, a somewhat contrasting color, there being a border 16 15 around the edge of the sheet of a similar contrasting color half the width of the dividing areas 14. These division lines 14, 16 represent the cement or plaster normally visible when vitreous tile is laid into a wall and the border 20 area is half the width of the so-called cement area since it abuts against a similar sheet and the two half width areas along the respective borders form the equivalent of a dividing area. Usually in a tile wall, the cement is tinted with 25 substantially the same color as the tile although appearing somewhat darker to the eye than the reflecting surface of the tile. Accordingly, in printing the design on the plane sheet, the dividing or cement areas 14, 16 are printed with the 30 same color as the squares 12 but of a slightly darker shade, or in a different color, as desired.

The sheet may be of any convenient material, such as a fibrous material, for instance, a heavy paper or cardboard, which may be pressed into 35 shape as illustrated, for instance, at 13 in Figure 4, but, conveniently, a relatively thin, flexible, printed sheet 15, Figures 5, 6 and 7, may be applied to the surface of a so-called backing sheet 17, Figure 5, and 36, Figure 6, for the backing sheet, but it has been found desirable to use either a heavy cardboard or a composite backing sheet such as an impregnated paper stock.

Applied to that surface of the sheet which will be exposed on the wall, is a layer or coating 13 45 of a material which is water resistant, which can be washed free of stains, even of grease and ink, without leaving a noticeable trace behind. The exposed surface of the sheet may be coated with a cellulose compound coating composition, 50 conveniently, a cellulose lacquer or cellulose acetate derivative or a synthetic resinoid or other water-proof, stain-proof and wear resistant coating 18. This may be put on as a solution in liquid or semi-liquid form either by means of 55

a roll or by spraying. The layer is then permitted to dry and harden. The coating may be applied in sheet form by heat and pressure. It is substantially transparent so that the coloring of the sheet 10 is visible therethrough. When heat is applied to such transparent sheet, it will permanently adhere to the surface of the forming sheet.

The various raised portions 12 representing tile may then conveniently be formed by an embossing operation. As illustrated in Figure 2, upper and lower embossing dies 20 and 22 are provided, the lower die having four (in the illustrated embodiment) spaced rectangular male portions or tables 24 and the upper die having downwardly depending ribs 26 to form the separating or cement areas 14, 16. These ribs may be conveniently covered by a material, such as leather 11, having a somewhat uneven surface, so as to give the surfaces 14, 16 of the paper, when embossed, a slightly irregular surface to simulate the somewhat uneven texture of cement. The formed sheet 10 and the water proofing layer 18 superimposed thereon or adhered thereto, as the case may be, is laid between the embossing dies and heat and pressure applied until the two sheets, if separate, are united and the laminated structure pressed into the shape illustrated in Figure 3 where the tile portions 12 are raised a predetermined degree above the cement areas to simulate tile set in a wall.

The raised tile areas 12 may then be reenforced as by filling the depressions therebehind, by which they are formed, with stiffening means, for instance, rectangular sheets of suitable reenforcing material, such as cardboard or fibre board 30, Figure 4, placed in the depressions and secured in place by a suitable adhesive.

If desired, a backing sheet 31 may be provided, of any convenient and cheap material, such as paper, which will overlie the surface of the same.

In Figure 5, the wall covering is illustrated as a composite structure formed by a sheet of corrugated paper 34 or the like having the usual surface sheets 36, 38 on opposite faces. One such surface sheet 36 corresponds to the backing sheet 17 and to it is applied the sheet 15 which is printed or otherwise decorated to represent tile. It is then coated in any convenient way with a moisture proof layer 18. Such a composite construction is embossed as a unit and when dividing areas 14 and 16 are formed in its surface by the dies, to represent the cement areas, the corrugations are crushed as shown at 42 while the uncrushed corrugations at 43 serve as the strengthening or reenforcing members. Such a sheet is satisfactory in many situations and is illustrated herein to show the wide range of compositions available for the purpose. The rear sheet 38 serves as convenient means whereby the wall covering of this modification may be secured to a wall.

The outwardly pressed tile simulating portions 65 may be reenforced by a plaster, say, plaster of Paris 28, Figure 6, in plastic form when the wall covering is to be applied to a wall by filling the cavities with the plaster and smearing it over the backs of the parts 14, 16 and then applying the sheets to the wall when the plaster dries and adheres to the walls of the depression and to the wall. Obviously any composition which may be applied in plastic form and which will harden and retain its form and permit the sheet to be attached to the wall quickly and easily and re-

main flat and not warp is within the purview of the invention. Such composition dries out without destroying the sheet and the sheet, when impregnated, does not become water soaked or buckle to such an extent that it is impossible to obtain a level surface.

In the preferred embodiment as now conceived, the formed sheet 10 is composed of a forty percent asphaltic composition and a sixty percent fibrous material, such as paper stock. Such a sheet is flexible and to a high degree water resistant.

The wall covering of this invention may also be formed without a reenforcement, or rather, by taking advantage of a greater thickness of a 15 backing sheet. Thus, as in Figure 7, a backing sheet 44 of a thickness greater, say, double that hereinbefore described and, preferably, of fibrous material impregnated with a compound of asphaltum or the like, is covered with a pervious 20 sheet 13 on which the representation of tile is depicted and overlayed with the impervious layer 18. This laminated structure is then embossed or otherwise treated to produce therein the raised areas 12 in simulation of tile set in a wall and 25 the depressed areas 14 in simulation of the cement areas. The depressed areas 14 then form ribs 46 as indicated in dot and dash lines in Figure 7, as will be understood. Subsequently, the rib portions 46 are cut off flush with the 30 lower surface 45 of the tile portions 12 whereby the raised portions 12 are solid although composite and the depressed areas 14 are materially thinner than the adjacent portions, as at 47. The thinner portions 47 lend a flexibility to the 35 sheet which enables it to conform readily to inequalities in the wall surface to which it is applied by an adhesive.

It may also be found desirable to so design the sheet of wall covering that the areas in simulation of cement appear only on two sides as at 48. 40 These may be of the same width as the areas 14 while the other two sides 49 are flush with the edge of the tile portions 12 and are adapted to abut against the areas 48 of adjacent wall covering sections. 45

It will thus be seen that a wall covering is provided which simulates tile and which may be formed in small areas. Each sheet preferably represents one or a plurality of tiles, the tile being separated or spaced by depressed portions representing the cement bonding the tile in an ordinary tile wall. The preferred material is water resistant to permit its application to a wall with an adhesive and at the same time it is 50 coated with a water-proof, stain-proof, wear resistant coating, which may be applied in any convenient fashion. Such representation of a tile may be readily made by embossing in embossing dies with the aid of heat and pressure and 55 the recesses forming the representations of the tile may be either filled with reenforcing material, such as rectangles of paper, cardboard, corrugated board or other material, or a plastic material which will harden in place, such as plaster of 60 Paris or the rear portion of the depressed parts simulating the plaster may be removed to provide a thicker tile portion and a thinner plaster portion.

Various modifications will occur to those skilled 70 in the art in the configuration, composition and disposition of the component elements going to make up the invention as a whole as well as in the selection or combination of elements of the various modifications into a component whole,

and no limitation is intended by the phraseology of the foregoing description or illustrations in the accompanying drawings.

What is claimed is:

- 5 1. The method of manufacturing a waterproof wall covering comprising printing on one surface of an opaque paper sheet rectangular areas bounded by dividing spaces to simulate tile set in a wall bounded by cement, affixing the unprinted surface of such sheet to a sheet of a composition containing an asphaltum composition and a fibrous stock, then applying to the printed surface a fluid water resistant, transparent wear resistant material to form a layer and pressing outwardly the representation of spaced tile by heat and pressure.
- 10 2. The method of manufacturing a waterproof wall covering comprising printing on one surface of an opaque paper sheet rectangular areas bounded by dividing spaces to simulate tile set in a wall bounded by cement, affixing the unprinted surface of such sheet to a sheet of a com-
- 15 3. The method of manufacturing a waterproof wall covering comprising printing on one surface of an opaque paper sheet rectangular areas bounded by dividing spaces to simulate tile set in a wall bounded by cement, affixing the unprinted side of said sheet to a backing sheet of a composition containing an asphaltum composition and a fibrous stock, then applying to the printed surface a fluid water resistant, wear re- 15
- 20 sistant material to form a layer, pressing outwardly the representation of spaced tile by heat and pressure thereby forming oppositely directed ribs behind the dividing spaces and cutting off said ribs substantially flush with the inner faces 20 of the recesses.
